UNITED STATES PATENT OFFICE.

JACOB H. LINVILLE, OF PHILADELPHIA, PENNSYLVANIA, ASSIGNOR TO THE INTERNATIONAL PRINTING TELEGRAPH COMPANY, OF CAMDEN, NEW JERSEY.

PRINTING-TELEGRAPH.

SPECIFICATION forming part of Letters Patent No. 350,984, dated October 19, 1886.

Application filed October 16, 1885. Serial No. 180,110. (No model.)

To all whom it may concern:

Be it known that I, JACOB H. LINVILLE, of the city and county of Philadelphia, in the State of Pennsylvania, have invented certain new and useful Improvements in Printing-Telegraphs, of which improvements the following is a specification.

My invention relates to a printing-telegraph system and apparatus of the class in which to rotating type-wheels controlled by escapements are used in connection with impression devices operated by electro-magnets, and so organized as to be employed for printing messages, stock-reports, and other financial or commercial matters with increased rapidity and accuracy in page form on sheets of paper, or upon continuous rolls of paper, in lines, in paragraphs, or in columns—that is to say, telegraphically printing messages, stock-reports, &c., similar in form and arrangement, on the transmitting-instruments simultaneously with their transmission to a receiving-instrument, or printing on instruments which may be combined or which may be so organized as to be operated interchangeably as a transmitter or receiver, or which may be so organized as to be operated as an independent transmitter or receiver, the change from a combined transmitting-instrument to a receiving-instrument being readily accomplished without auxiliary gearing or motive power, through the manipulation of a switch, as hereinafter fully explained.

My invention consists, generally, in the organization of the following systems of apparatus, and of combining in one or more instruments all or any of the specific features as may be desired for the particular purpose, embracing, first, a paper-carriage with suitable feeding mechanism applicable to and susceptible of use in such combined transmitting and receiving instruments or in separate and independent transmitting and receiving instruments for telegraphically printing on flat pages, &c., from a continuous roll of paper; secondly, improved devices for feeding the paper to space between lines by the recoil movement of the carriage during its excursion; thirdly, suitable mechanism for bringing the paper-carriages of any number of receiving-instruments into unison for cutting out of circuit all

of the instruments connected in a continuous circuit, and for closing the circuit or circuits of such particular instruments as it may be desired to print the message on, through suitable mechanism and electrical devices operated from any transmitter in such series of instruments; fourthly, a novel construction of indicator-plate in a transmitting-instrument, with radial circuit-closing arms and character-rods actuated by the depression of any character-key, as will be hereinafter more particularly explained, and, finally, the organization of the electrical circuits for operating any or all of the combined instruments as receivers from any transmitter in the series, or for operating any number of instruments organized as receivers on separate lines radiating from a transmitter located at a central station.

The paper-carriage carrying the roll of paper upon which impressions are to be made traverses backward and forward on a platform extending from the rear of the transmitting or receiving instruments or combined instruments, and supports the paper-rollers, circuit-interrupting switches, feeding-rollers, and mechanism operating therewith, and having guides for supporting the paper in a vertical position behind the type-wheel and contiguous thereto, so that the impressions made upon the paper occupy an unobstructed view at all times in front of the operator on a transmitting-instrument, and the impressions recorded on a receiving-instrument are in like manner visible to and convenient for reference by recipients, thereby rendering the invention especially valuable for recording long messages, stock-quotations, &c.

When a series of page-printing telegraph-instruments are employed on continuous telegraphic lines, it becomes necessary to bring the respective paper-carriages to unison, in order that all the instruments may commence spacing letters in a line from similar points with reference to the margin of the paper on all of the instruments. To accomplish this result it is essentially requisite to lock each paper-carriage at a predetermined point, or preferably at the end of its retrograde movement, and to maintain it in such position until all the carriages in the series are in similar positions, and then, by simultaneously releasing

the respective carriages, to cause them to travel in unison.

It is essential in printing-telegraphs to provide means whereby a transmitting-operator 5 may be capable of cutting out of circuit all the receiving-instruments in a series, and of connecting in circuit *ad libitum* the particular receiving-instruments in the series on which it may be desired to record the im- 10 pressions.

Without a unison device page-printing in paragraphs in columns, &c., in a series of connected instruments is impracticable, and without a "cut-out" and circuit-closing de- 15 vice to individualize the instruments the same message would be printed simultaneously on all the instruments, involving expensive waste, unnecessary resistance in the circuit, and an appreciable increase of battery-currents, and 20 especially obviating the essential requirement of secrecy in transmission.

To overcome these objectionable features is one of the objects of my invention, which I accomplish by utilizing the force of the re- 25 coiling paper-carriage for breaking the circuit through the operative electro-magnets of the receiving-instruments at the moment the left-hand margin of the paper has been reached, and automatically shunting the line-circuits 30 by branch lines running in reverse directions through the coils of a differential electro-magnet, one coil of which electro-magnet revolves the circuit-closers by a step-by-step or ratchet movement, and when these circuit-closers are 35 revolved to a predetermined point in their peripheries they close the main lines around the "break" and through the electro-magnets of any instrument to which it may be desired to transmit a message, leaving the re- 40 maining receivers in the series inoperative, or they close the circuits of all the instruments in the series simultaneously after the paper-carriages have been brought to unison. Motion is imparted to the revolving circuit-clos- 45 ers by a differential electro-magnet in the branch circuit through which is sent over one line a number of electrical pulsations corresponding to the number of the instrument in the line which it is desired to bring into cir- 50 cuit, or to print on, numbering, of course, from a terminal station. One pulsation brings a single metallic bearing on the insulated circuit-wheels into contact with circuit-springs which close the line around the break to the 55 instrument numbered, say, one, without, how- ever, breaking the branch circuit. Two pulsations break this circuit again in number one, rotating the metallic bearing of number two in to contact with its circuit-closing springs, and 60 so on in succession, one instrument of a higher number is brought into circuit and the preceding one disconnected until the instrument is reached on which it is desired to print the mes- 65 sage. This restores the main circuit through the circuit-closing device until one pulsation is sent simultaneously over both lines by the releasing-key, or otherwise, which, while re-

leasing the unison-latch of the type-wheels, closes the local printing-circuit, operating to move the paper-carriage one notch, thereby 70 breaking the branch main-line circuit through the circuit-closing electro-magnet, and restoring the original line to that particular instrument. The circuit-breaker to send pulsations is preferably a revolving circuit-breaking 75 wheel with as many makes and breaks as there are instruments in the line, and with a registering-dial on which is indicated the number of instruments connected in series or otherwise. A pointer on this dial indicates the 80 number of pulsations sent to line and the relative movement of all the circuit-closing devices. The circuit in the transmitter to this circuit-breaker is a branch of the main line normally broken when the circuit-breaker is 85 stopped on a break or at zero.

After the transmission of a message each individual operator turns his circuit-breaker to zero, thereby enabling any operator starting from the zero-point to revolve the circuit-closers of all the instruments in the series until the desired receiving-instrument, as indicated on the dial operated, is in circuit. All the instruments, or any number, may be 90 simultaneously connected by adjusting the circuit-closing contacts in the revolving disks so as to close the circuits simultaneously. To bring the circuit-closers to the same initial point, or to unison, a mechanical device is placed on the shaft of the circuit-closers, which 95 locks it at a point corresponding with the zero of the dial, and an ordinary electro-magnet is placed in the first branch circuit above mentioned, with both lines passing independently through its respective coils, rendering it inoperative by impulses on one line while the differential electro-magnet is rotating the circuit-breaker, yet operative to release the unison-latch when impulses are sent on both lines, 100 rendering the differential electro-magnet inop- 105 erative.

Since pulsations on both lines simultaneously render inert the differential electro-magnet, the contact on the circuit-closer will not be moved when pulsations are sent to 115 move the paper-carriage. The main-line circuits in the transmitter are broken at the main-line circuit-breaker when the type-wheels stand at unison during this operation.

The transmitting-instrument may be organized similarly to the other instruments, and its circuit-closers operated synchronously. One of the main-line circuits is normally connected through the coils of an electro-magnet which responds only to prolonged impulses on this 120 line, its armature-lever being linked to a rock- 125 ing arm held laterally by fixed jaws, and through which a square shaft carried by the paper-carriage freely moves. This shaft actuates levers and pawls, which, at each impulse 130 through this electro-magnet (at any position of the paper) revolves the feed-rollers one notch, feeding the paper the space between two lines. The other main line is normally

connected through another electro-magnet, responding only to prolonged pulsations, the armature-lever of which magnet is coupled to a shaft to which the automatic device for releasing the paper-carriage is attached. One prolonged impulse on this line releases the paper-carriage at any point in its excursion, allowing it to recoil and feed the paper a space between two lines.

10 In the accompanying drawings, illustrating my invention, Figure 1 is a top or plan view of a transmitting-instrument, showing the key-board and keys and operative mechanism embraced therein. Fig. 2 is a side elevation, 15 partly in section, of the same. Fig. 3 is a top or plan view of the paper-carriage and mechanism operating therewith. Fig. 4 is an end view of the paper-carriage, showing in conjunction therewith the individualizing mechanism and electro-magnetic devices for operating the same. Fig. 5 is a rear elevation of the same. Fig. 6 is a top view with the platform removed, showing the circuit-breaker and unison-stop of the individualizing mechanism. 20 Fig. 7 is a detailed view of the unison fusee or spiral. Figs. 8 and 9 are respectively theoretical diagrammatic views showing the arrangement of the electrical circuits and operative mechanism embodying my invention in 25 combined transmitting and receiving instruments. Fig. 10 is a front elevation of the dial-plate and individualizing circuit-breaker; and Fig. 11 is a longitudinal section of a combined transmitting and receiving instrument, showing, also, the paper-carriage and paper-feeding and individualizing mechanism.

In order that the description and operation of the receiving-instrument may be fully appreciated, I will now describe, by reference to 40 the drawings, the principal features and elements embodying a transmitting-instrument and the mode of transmitting currents of electricity to a receiving-instrument.

A key-board, B, rigidly secured to the base-plate A of the instrument, is arranged somewhat similar to the key-board of a type-writing machine, with buttons, arranged in concentric arcs, on which are engraved letters, figures, punctuation-marks, &c., with blank 45 and unison keys, also arranged in concentric arcs, with a blank key, b, for spacing between words, a unison-key, b', for releasing the insulated rod b², a key, b³, for releasing the insulated unison-rod b² and unison-latch h⁶, a key, b⁵, for spacing between lines, a key, b⁶, for releasing the paper-carriage A³ at any point in its excursion, a key, b⁷, for spacing between lines at any point in the excursion of the paper-carriage, a key, b¹⁰, for releasing the unison 55 of the individualizing circuit-breaker, and a key, b⁸, for duplicating letters.

The type-wheels C have letters, figures, punctuation-marks, and blank and unison spaces corresponding to the characters, figures, &c., on the key-board B.

The character-keys, arranged concentrically

on the key-board B, operate bell-crank levers b⁹, resting upon a series of bearings, b¹⁰, rigidly secured to the curved guides b²⁶ at different radii under the character-keys, and imparting longitudinal motion to the respective series of rods b¹¹, equal in number to the character-keys, lying horizontally and radiating from the same common center in which is placed the shaft b¹² of the line-circuit breaker. Concentric 75 therewith is placed a metallic segment of a cylinder, b¹³, preferably perforated with square holes b¹⁴, in series directly over each other and equally distant from one another—that is to say, from center to center—the entire number 80 of holes b¹⁴ being equal to the divisions on the type-wheels C. These rods b¹¹ pass through the curved guides b²⁶, that form the steps therefor, and are limited in their forward movement by shoulders b¹⁵, abutting against the metallic segment b¹³, or pins b²⁷, abutting against the fixed guides b²⁶, the rods b¹¹ being normally held back by spiral springs b¹⁶ against or connected with one branch of the bell-crank levers b⁹, the other branch supporting the key-stems b¹⁷, through which pass pins b¹⁸, limiting the backward throw of the character-keys and rods b¹¹, and thereby bringing the terminals of these rods clear of the interior surface of the metallic segment b¹³.

95 On the indicator-shaft b¹², carrying the circuit-breakers N N', are as many metallic arms b¹⁹ as there are series of holes b¹⁴ in the metallic segment b¹³, these arms b¹⁹, being secured to an insulated hub, b²⁰, on the indicator-shaft b¹², 100 and located in the same horizontal planes with the respective banks of rods b¹¹, and on equal divisions of the circle corresponding with the number of banks of these rods. One of these rods b¹¹ is a unison-rod, b², and is not operated 105 by a character-key, but has a backward motion to the forward one of a character-key, and vice versa, imparted to it by a rock-shaft, b²¹, with depending arms b²² passing alongside of each radial line of rods b¹¹, which is moved forward 110 by pins b²³ in the rods b¹¹, giving a reverse motion through a lever, b²⁴, on the same shaft, and a link attachment, b²⁵, to the depending lever b²⁶, which, by a pin, b²⁷, on the unison-rod b², withdraws it upon the depression of any 115 character-key. The end of the unison-rod b², passing through the metallic segment b¹³, is made of insulating material.

The circuit-breaker, escapement, compound, differential, printing, ratchet, and relay magnets, scape-wheels, spacing-wheel, clutches on a loose sleeve on the type-wheel shaft, centrifugal adjustable governor, paper-spring, and mechanism for actuating and operating these several elements and parts, form the subject- 125 matter, in conjunction with certain other features, of an application for a patent, Serial No. 175,131, filed by me under date of August 24, 1885; and I therefore do not wish to be understood as claiming these several elements 130 and parts herein separately, but only in connection with new and improved features to be

hereinafter fully described, which form in conjunction therewith the subject-matter of this application.

On the indicator-shaft b^{12} is a circuit-breaker, N, single for single-line instruments, and double for instruments operated by double lines and escapements. As the type-wheel C revolves, the circuit-breakers N N' on the indicator-shaft b^{12} send electrical pulsations over the lines to operate alternately the escapement electro-magnets I and I', the compound or duplex relays H H', and differential electro-magnets J J', and rotate the type-wheels C, while pulsations on both lines, simultaneously closed by the electro-magnet G, operate both the electro-magnets H H', closing the local circuits to energize the paper-feeding electro-magnets and the printing electro-magnets of the receivers in combined or independent instruments. The bars b^{19} , insulated from the indicator-shaft b^{12} , revolve so as to strike against any one of the character-rods b^{11} which may have been projected by the depression of a key beyond the surface of the indicator-segment b^{13} into the path of the revolving arms b^{19} , and also to strike the insulated unison-rod b^2 when none of the keys have been depressed. A circuit-spring, b^{30} , bears on the insulated hub b^{20} , carrying these arms b^{19} , and is connected with the binding-post b^{31} , insulated from the machine.

When a key has been depressed, the type-wheel C of the transmitter revolves as many characters as there are rods b^{11} between the starting-point or unison-rod b^2 and the character depressed. When it is stopped by the pin represented by the key and metallic rod b^{11} , the circuit is closed from a local battery, Q, (one pole of which is in circuit with the body of the indicator-segment b^{13}), through the springs b^{30} , line l^{29} , electro-magnet G, line l^{30} , key b^3 , line l^{26} , spring s^{12} , to the metallic block marked to "send" on the insulated commutator S, thence by spring s^{11} , through line l^{32} , to the ratchet electro-magnet E, and thence to the impression electro-magnets D, and returning by line l^{33} to the other pole of the local battery Q. This energizes the ratchet electro-magnet E and the impression electro-magnet D of the transmitter, and causes the printing-hammer d' to impress the paper against the type-wheel C, printing the desired letter as depressed on the key-board B, and as indicated by the rod b^{11} in the indicator-segment b^{13} , while the ratchet electro-magnet E draws back the arm a^8 . When the key is restored, the withdrawal of the rod b^{11} breaks the electrical contact, the hammer d' recoils, the spring a^3 withdraws the arm a^8 , and the pawl a^2 , catching in a rack, A⁶, in the paper-carriage A⁵, moves the same the space between the letter printed and the succeeding letter. The ratchet electro-magnet E is secured to the platform A', carrying the paper-feeding mechanism.

When the type-wheels C of the transmitter and receiver have been stopped at the letter depressed, the local circuit of the transmitting-instrument is automatically closed, as de-

scribed, which energizes the electro-magnet G, attracting its tongue g^4 , on which is an insulated bar, g^5 , for bringing the circuit-springs g^6 g^7 g^8 into contact, closing the circuit into both main lines simultaneously through branch lines l^{11} l^{12} l^{13} l^{14} , passing around the circuit-breakers N N', through lines l^{15} and l^{16} , to the compound or duplex relays H H', closing the local circuits by the relay-tongues h and the contacts h' through the ratchet electro-magnets E and printing electro-magnet D of the receivers in circuit, and simultaneously making impressions and feeding the paper the space between two letters on the transmitter and receiver.

The paper is normally held out of contact with the type-wheel C by an adjustable spring, c^2 , secured to the top plate, c^3 , of the machine by a pivoted stud, c^4 , adjustable by a slotted arm, c^5 , moving on a stud-pin, c^6 , on which is a clamping-nut, c^7 , for adjusting the spring c^2 to its proper position. When the printing-hammer d' strikes the paper C, this spring c^2 is pressed backward under the type-wheel C, and when the hammer d' recoils the spring c^2 moves the paper C out of contact with the type-wheel C, thus regulating the distinctiveness of the impression, preventing blurring, and enabling the printing to be done on flat surfaces.

The specific features embodying my invention will now be hereinafter more particularly explained.

In the drawings, Figs. 8 and 9, as aforesaid, represent theoretical diagrammatic views of the principal operative devices and circuits in a combined instrument, or in separate or independent transmitting and receiving instruments connected with line and local batteries, showing the indicator-segment and circuit-breaker of the transmitter, and devices for sending currents to a distant receiver, and for printing simultaneously on both instruments. The switch S² and the commutators S and S' in Fig. 8 are shown as turned to send and the local circuit closed to operate the printing devices of a transmitter, and to send impulses to the line of a distant receiver. If the switch S² in Fig. 9 be turned to line marked to "receive," the circuits will be changed by the commutators S and S', so that the currents from line will operate the compound or duplex relays H H', the escapement electro-magnets I and I', and both branches of the differential electro-magnets J J' alternately, and the local circuit from the body of the instrument by line, as shown in Figs. 8 and 9, indicating electrical connection through the same into the tongue h , thence through contact h' , line l^{10} , springs s^{10} , metallic block marked to "receive," spring s^8 , lines l^{21} , l^{22} , and l^{23} will operate the printing electro-magnet D and ratchet electro-magnet E of a receiver. Turning the switch S² to receive also disengages the insulated unison-rod b^2 in the indicator-segment b^{13} of a combined instrument, and engages a clutch, c^{25} , on the type-wheel shaft c with the loose

sleeve on the same, carrying the scape-wheels C^3 C^4 , together with the star or letter-spacing wheel C^5 and disk-wheel C^6 , with the spiral C^7 for the unison-latch h^6 .

5 I and I' are escapement electro-magnets, which vibrate alternately by rapid alternating impulses of direct current sent over the lines by the circuit-breakers N N' and springs n n' n'' n''' . Their armatures operate double-pallet 10 "dead-beat" or wedge-pallet escapement-levers i i' , each working into separate scape-wheels C^3 C^4 on the same shaft, e , so arranged that each electrical impulse permits the advance of the type-wheel C the space between 15 two letters, and each break of the circuit a similar movement. There are half as many makes and breaks on each disk of the circuit-breaker and one-fourth as many teeth on each scape-wheel as there are divisions on the type-wheel when two escapements are used, and the instruments are so arranged that they print a letter on each make or break of the electrical circuit.

The compound or duplex relays H H' perform the function of drawing the tongue h into contact with the printing-circuit contact h' when energized by the combined currents simultaneously entering at the binding-posts p p' through the lines l^{23} l^{24} , leading from a transmitter, and from these binding-posts the currents pass by lines l^{25} l^{24} to the springs s^7 s^8 , contacts marked "receive" of the commutator S , and spring s^4 , thence by line l^{19} through the electro-magnet L , thence by line l^{18} to the differential electro-magnet J , thence, say, to the right around the differential electro-magnet J and by line l^{17} through the coils of the escapement electro-magnet I , and thence by line l^{16} through the coils H of the compound relay, 40 and thence, again, by the line l^{15} to junction with the main line l^1 , the other line, l^{22} , from the spring s^5 passing through the electro-magnet K , thence by line l^{21} to the differential electro-magnet J' , thence passing in a reverse 45 direction, say, to the left, around the differential electro-magnet J' and by line l^{20} to the coils of the escapement electro-magnet I , thence again by line l^{19} around the coils H' of the compound relay to the line l^{16} , and thence to the main line l^6 , as hereinafter more fully described. When the currents enter alternately by these 50 lines, the two distinct electro-magnets H H' comprising the system are energized alternately, resulting only in the vibration of the compound armature-lever h^3 , (to which the tongue h is connected by a pivoted strap-coupling, h^4), without moving the tongue h . Coupled to the tongue h is a bell-crank lever, h^5 , pivoted at one end, and its arm b^4 extending over 55 the horizontal disk-wheel C^3 , Figs. 8 and 9, which has a spiral groove and projection, into and against which bears a pin on the unison-latch h^6 , rocking on the support h^7 , and drawn downward and sidewise toward the shaft e of 60 the type-wheel C by springs h^8 in the side and below said latch, respectively. As the type-wheel revolves, the spiral carries the uni-

son-latch h^6 toward the periphery of the disk-wheel C^7 , and by one or more revolutions it reaches the end of its path and locks the type-wheel C at unison with the type-wheel C of the transmitter. If, however, the compound or duplex relays H H' be energized by both line-currents simultaneously, both armatures will be attracted, and the tongue h will be drawn 70 forward, tripping the unison-latch h^6 by the bell-crank lever h^5 out of the groove of the spiral C^7 , whereupon the arm h^6 is thrown against the shaft of the type-wheel C , and thus begins its travel anew on the spiral; hence 75 it is evident that the unison-latch h^6 cannot lock the type-wheel C , if simultaneous printing-currents are sent one or more times during one revolution of the type-wheel.

Since it is necessary to send such impulses 80 to make spaces and impressions, or to rotate the paper-cylinder, which should be done at a space or at unison, and since vibrations alternately over the lines are necessary to rotate the type-wheels to unison, and since printing 85 is to be effected on makes and breaks of current, some other device is required, not only to hold the type at a blank space or at unison while printing-currents are simultaneously sent over the lines actuating the tongue h , (displacing the unison-stop and closing the local circuit of the receiver,) but to hold the type-wheel 90 C rigidly at each character to be printed on breaks of line-circuit, and to release it by continually vibrating or attracting the armature 95 while alternate impulses are passing over the lines through the escapement-magnets I and I' . The differentially-wound relay J , with its tongue j and arm j' , is such a combination as is well adapted for effecting these results. The 100 line-wires pass in opposite directions around the cores of the differentially-wound relay J . The serrated or letter-spacing wheel C^5 has as many indentations as there are characters and blank spaces on the type-wheel C . This differentially-wound relay J will become charged 105 by the rapidly-recurring alternate impulses, yet will be inert when currents pass in both directions around its cores, and by its lug or projection j^2 and spring j^3 lock the type-wheel 110 C at any indicated character-space when the printing-current is sent simultaneously over the lines, and will also lock it at blank or unison when once stopped at unison by the unison-latch h^6 . It cannot alone arrest the 115 type-wheel C at unison, because its armature is permanently attracted or vibrated by the alternate impulses required to move the scape-wheels C^3 C^4 ; but it can lock the type-wheel C at any letter or space when printing, or 120 when the compound relays H H' are energized by currents sent simultaneously over the lines to close the local circuit through the ratchet and printing electro-magnets.

The type-wheels C are brought into unison 125 by withdrawing the unison-rod b^2 of the transmitter through the action of the unison-key b' , thus permitting the circuit-breakers N N' to make one or more revolutions before releasing

the unison-rod b^2 . After allowing the receiver to stop at unison the latch cannot be released, except by simultaneous electrical impulses on both lines. To prevent the operator from 5 "sending" before the type-wheel of the receiver is released, I employ a unison-key, b' , normally locking the unison-rod b^2 , and preventing any character-keys from being depressed. Before sending, the operator presses 10 the releasing-key b^3 , the block b^{33} on the stem of the key b^3 , releases the unison-rod b^2 and character-keys, the insulation b^{32} on the back of the block b^{33} compressing the circuit-springs $s^{14} s^{15}$, closing the branch local circuit t^{37} through 15 the circuit-springs $s^{16} s^{17}$, closed by the unison-rod b^2 and by lines $t^{38} t^{34} t^{37} t^{35} t^{30}$, springs $s^{12} s^{11}$, and line t^2 , energizing the electro-magnet G, which closes the circuit of both lines through 20 the receiver, releasing the unison-latch h^6 , but leaving the type-wheels C locked at unison by the arm j' on the tongue j of the differential electro-magnet J. The keys are now operated successively, keeping the unison-rod b^2 withdrawn until it is necessary to effect unison. 25 To avoid a closed circuit through the electro-magnet G after the type-wheel C and circuit-breakers N N' start, the local branch circuit t^{37} is automatically broken by the separation of the circuit-springs $s^{16} s^{17}$, when the unison-rod 30 b^2 is withdrawn.

A platform, A', is secured to the rear end of the base-plate A, having a supporting-frame, A², for certain parts of the instrument. Upon said platform A' are rails a , on which the 35 paper-carriage A³, supporting the paper-rollers A⁴, paper-guides A⁵, rack A⁶, and circuit-springs $z^5 z^6$ traverse, carrying and feeding the paper on which impressions are to be made in a flat sheet, C', in a vertical direction in front 40 of the type-wheel. Forward motion step by step to space between letters is imparted to the carriage by the lever a^8 and pawl a^2 , working in the straight rack A⁶, the reciprocating motion of the lever a^8 and pawl a^2 being effected 45 by the ratchet electro-magnet E and spring a^9 . A dog, a^4 , retains the rack A⁶ in position at each throw of the lever a^8 and pawl a^2 . The forward movement of the carriage is resisted by a coiled spring, a^5 , or it may be by a weight, 50 a^{36} , attached to a cord passing over a pulley, a^{36} . This coiled spring is secured upon a shaft, a^6 , attached to the platform A', one end of which spring is secured to an arm, A⁷, depending from the carriage-frame A³.

55 As the carriage A³ moves forward upon the rails a , so as to feed the paper from left to right hand margin in front of the type-wheel C, the tension of the coiled spring a^5 is increased, so that it is sufficient to return the 60 carriage to its initial starting-point when the pawl a^2 and dog a^4 have been automatically released. Attached to the rear portion of the instruments is a straight inclined plane, a^{10} , the projecting flange a^{11} of which fits loosely 65 into a notch, a^{12} , of the arms a^{13} , attached to the sliding pawls a^{14} , causing a vertical reciprocating motion of the arms a^{13} and pawls a^{14}

by the traversing movement of the carriage without the intervention of springs on the arms, thus obviating unnecessary resistance of 70 springs on the arms a^{13} to withdraw the pawls. As the paper-carriage A³ recoils under the influence of the coil-springs a^5 or a weight, the arms a^{13} and pawls a^{14} are given a downward movement, imparting a rotary motion to the 75 ratchet-wheels a^{15} , feed-rollers a^{16} , and guide-rollers a^{17} , moving the paper forward and upward the space between two lines of the printing. The dogs a^{18} retain the ratchets a^{15} in position during the printing of another line, 80 while the pawls a^{14} are gradually drawn upward by the plane until they enter the next notch or tooth of the ratchet-wheels a^{15} , just, however, before the carriage again recoils.

The pawls a^2 and dog a^4 are released from the 85 rack A⁶ by means of a tripping device consisting of the T-shaped bar a^{19} and the two pins $a^{20} a^{21}$ upon the upper side behind the pawl a^2 and dog a^4 , and pin a^{22} , extending downward to engage in the latch a^{24} . The T-shaped bar 90 a^{19} is pivoted to a shaft, a^{25} , extending through the platform, and is driven forward under the pawl a^2 and dog a^4 by a projection, a^{26} , on the carriage A³, striking the projecting pin a^{22} , and causing it to become locked through the action 95 of the latch a^{24} . In this position the dog a^4 is detached by means of the pin a^{21} , and the pin a^{22} engages in the spring-latch a^{24} , retaining the dog a^4 out of position with the rack A⁶, and the next attraction of the armature and lever a^8 of the ratchet electro-magnet E detaches the pawl a^2 from the rack A⁶, causing 100 it to lock on the pin a^{20} . The carriage A³ immediately recoils, and just before it reaches the end of its travel a stud, a^{27} , on the carriage 105 A³ depresses the spring-latch a^{24} , permitting the T-shaped bar a^{19} to return to its normal position under the action of a spring, thus releasing the pawls a^2 and dog a^4 , which resume 110 positions in contact with the rack A⁶, ready to commence spacing between letters from the left-hand margin of the paper.

The plates Z are made of hard rubber or other suitable insulating material, and have projecting ribs $z z'$, which are secured to the 115 carriage-frame A³ and move in unison therewith. Above these projecting ribs or flanges $z z'$, at one end thereof, are two long metallic springs, $z^2 z^3$, standing free from the faces of the plates Z and pressing at one end on metallic bearings z^4 on the projecting flanges $z z'$. The insulated springs $z^5 z^6$, attached to the platform A' by insulated supports z^7 , bear at 120 their ends on the springs $z^2 z^3$, and at right angles thereto preserving electrical contact 125 during the forward movement of the carriage A³, breaking or interrupting the circuit of the main lines during the recoil of the carriage and closing the circuit just before the carriage completes its backward movement. The insulated springs $z^5 z^6$, having a downward tendency, press on the upper surfaces of the springs $z^2 z^3$ until they arrive at the ends of their 130 path clear of these springs when they snap

downward into contact with the metallic bearings z^9 in electrical connection with the springs $z^2 z^3$. By the return movement of the carriage 5 the insulated springs $z^5 z^6$ are made to travel the insulated shelves $z^1 z^2$, passing under the ends of the springs $z^2 z^3$ on the metallic bearings z^4 , ready to again ride upward over these circuit-springs by the next forward movement 10 of the paper-carriage A³. The printing-hammer d' is operated by the electro-magnet D in the same local circuit with the ratchet-magnet E.

The operation of the apparatus when printing will now be described by reference to the 15 theoretical diagrammatic views of two combined instruments and electrical circuits, illustrated in Figs. 8 and 9 of the annexed drawings, showing the operative parts and circuits, when in the former view the switch S² is set 20 to send, and while in the latter view the switch S² in a similar instrument is set to receive; both instruments being connected in series by a double telegraphic line; or the instruments may be two of a series of instruments 25 looped into the main lines. The line-battery may be either located at one end of or on the lines, and the electrodes connected to earth at the terminal stations. The double lines from the main-line battery M are connected to earth by line l', and to the binding-posts p p' by lines l² l³; thence by lines l⁴ l⁵ to the circuit-springs s s' in contact with the metallic blocks marked to "send" on the commutator S of the transmitter; thence to the 30 springs s² s³ by lines l⁶ l⁷ to the circuit-breaking springs n n' on the circuit-breakers N N'; thence by springs n² n³ to lines l⁸ l⁹ to the automatic circuit-breaker O through springs o o, o', and o" to lines l¹⁰ and l¹¹, springs z² and z³ and by 35 springs z⁵ and z⁶ to lines l¹² and l¹³; thence to the line binding-posts p² p³. Branch circuits l¹⁴ l¹⁵ extend from the springs n and n' to the circuit-springs g and g', thence by springs g² and g³ when closed by the movement of the tongue 40 of the magnet G and lines l¹⁶ and l¹⁷ to the main lines l¹⁰ and l¹¹. The branch lines l¹⁵ and l¹⁶ in this instrument, operative when employed as a receiver, Fig. 9, enter at the binding-posts p p', and are connected to springs s⁷ s⁸ by 45 lines l¹⁸ l¹⁹, and when the commutator S is turned to receive metallic contact is made with the springs s⁴ s⁵. The commutator S being turned to receive, the main lines l¹⁰ l¹¹, operative in a transmitting-instrument, are broken 50 at the commutator S, and the main lines l¹⁰ l¹¹ through the circuit-breakers N N' and lines l¹⁰ l¹¹ to the commutator-springs s² s³. From spring s⁴ one line of the receiving-circuit passes by line l¹⁹, magnet L, line l¹⁸ in one direction—say to the right—around the differential magnet J; thence by line l²⁰ through the coils of the escapement-magnet I'; thence by line l²¹ through the coils H of the compound relay; thence by line l²² to intersection with 55 the line l¹; thence to the circuit-breakers O and Z and the binding-post p² by the main line hereinbefore described, the other line, start-

ing from spring s⁵ of the commutator S, passing by line l²³ around the coils of the electro-magnet K; thence by line l²⁴, passing in a reverse direction—say to the left—around the differential electro-magnet J'; thence by line l²⁵ to the coils of the escapement electro-magnet I; thence around the coils H' of the compound relay, and by line l²⁶ to intersection with the main line l¹; thence by circuit-breakers O Z, line l¹, to the binding-post p².

The main lines l²⁵ and l²⁶ connect with the receiving-instrument at the binding-posts p and p', Fig. 9, passing through the springs s⁷ and s⁸ and s¹ and s² in electrical connection through the metallic block receive on the commutator S, in the same direction as that just described for transmitting through the magnets K, L, J J', I I', and H H', lines l¹³ and l¹⁶, (the lines l⁶ and l⁷ now being normally broken at the commutator-block marked "Send";) thence to circuit-breaker O, springs o o and o' and o"; thence by lines l⁸ and l⁹ to the circuit-breakers Z, through springs z², z³, z⁵, and z⁶, lines l¹⁰ and l¹¹ to the binding-posts p² p³, from which the lines may be extended by lines l²⁵ and l²⁶ to another instrument, or through a series of instruments or to earth.

A local battery, Q, is required at each transmitting-instrument to energize the electro-magnet G, for closing both line-circuits simultaneously through the electro-magnets H H' of the receiver, in order to close the local circuit through the ratchet electro-magnet E and printing electro-magnet D, for feeding the paper and for making impressions. One pole of the local battery Q of each instrument is connected by line l²⁷ to the binding-post p⁴; thence by line l²⁸ to an uninsulated post, b¹⁵, on the indicator-segment b¹³; thence, when contact is made between arm b¹⁹ and a character-rod, b¹¹, by insulated arm b¹⁹, hub b²⁰, circuit-spring b²⁰, to the insulated post b²¹; thence by line l²⁹ through the coils of electro-magnet G; thence by line l³⁰ through the duplicating-key b⁸ to the circuit-spring s¹², metallic block marked to "send" on the commutator S', circuit-spring s¹¹ to line l³², ratchet electro-magnet E; thence to printing electro magnet D, returning by line l³³ to the binding-post p⁵, and by line l³⁴ to the other pole of the local battery Q.

In the receiving-instrument, with the commutator S' turned to receive, the local circuits pass by line l³⁵ into the body of the instrument at the uninsulated post b³⁵ on the indicator-segment b¹³, the insulated arms b¹⁹ of which now rotate out of contact with circuit-closing character-rods b¹¹. The current from the body of the instrument passes by a line, as indicated in Figs. 8 and 9, connecting the same with the compound or duplex relay-tongue h, and to the contact h', insulated post h², line l³⁶, to spring s¹⁰, to the metallic block marked to "receive," Fig. 9, and spring s⁹, lines l³¹ and l³², to the ratchet electro-magnet E and printing electro-magnet D, and returning by line l³³ to the binding-post p⁵, thence by

line l^{23} to the other pole of the local battery Q. In the receiver this circuit is closed by the action of the compound relays H H', closing the tongue h on the contact h' , when these electro-magnets are energized by pulsations on both lines simultaneously. The branch local circuit employed only in transmitting instruments starts at the post p^5 on the indicator segment b^{13} , and passes by line l^{24} to the key b^5 , normally open, thence by line l^{25} to the electro-magnet G, through this electro-magnet and line l^{26} to the key b^8 , normally closed, to line l^{26} , circuit-spring s^{12} , to the block marked to "send," spring s^1 , line l^{22} , ratchet electro-magnet E, and printing electro-magnet D, line l^{23} , to the post p^5 , and thence by line l^{23} to the local battery Q. The extension or secondary branch extends from one end of key b^5 by line l^{27} , and is closed at the springs s^{14} and s^{15} by pressing the releasing key b^3 and insulated cam b^{22} of the transmitter, and is normally closed at the springs s^{16} and s^{17} , and automatically broken at these springs s^{16} s^{17} by the first movement of the insulated rod b^2 , withdrawn by pressing any character-key. This secondary branch is closed from springs s^{16} through line l^{22} with the trunnions of key b^5 and line l^{23} of the primary branch local circuit. Pressing the releasing-key b^3 closes the secondary branch of the local circuit l^{27} at the springs s^{14} s^{15} , energizing the electro-magnet G, and the current sent over both main lines is available in the receiver, not only for releasing the unison-latch by energizing both branches of the duplex electro-magnets, but for closing the local circuits at the contact h' through the ratchet electro-magnet E and printing electro-magnet D, thereby moving the paper-carriage A^3 one notch on the receiver, and this secondary branch local circuit l^{27} being closed by its primary circuit through the metallic block marked to "send" in the transmitter, Fig. 8, springs s^{12} s^1 , and line l^{22} through the ratchet electro-magnet E and printing electro-magnet D, moving the paper-carriage one notch on the transmitter.

When a character-key has been depressed, the double circuit-breakers N N' revolve, sending pulsations alternately over the lines to operate the escapement electro-magnets I and I', Fig. 9, and to cause a synchronous movement of the type-wheels C. When any arm, b^{19} , Fig. 8, strikes a projecting character-rod, b^{11} , in the indicator-segment b^{13} , the circuit from the local battery Q is closed through lines l^{28} l^{29} , electro-magnet G, lines l^{20} l^{26} , to the spring s^{12} , block marked to "send" of the commutator S, spring s^1 , line l^{22} , ratchet electro-magnet E, and printing electro-magnet D of the transmitter, causing the lever-arm a^8 and the pawl a^2 to be drawn backward so as to engage in a notch in the rack A^6 and the hammer d' , to impress the paper against a character on the type-wheel C. The electro-magnet G, being energized, closes both branches of the main lines l^1 l^2 simultaneously through the springs g , g' , g^2 , and g^3 of the transmitting

instrument with lines l^{13} , l^{14} , and l^6 , and l^7 , l^8 , l^{25} , and l^{26} to the receiver, and the local circuit from the body of the receiver is closed by the action of the duplex relay H and the tongue h and contact h' through line l^{10} , spring s^{10} , metallic block marked to "receive," spring s^9 , lines l^{21} and l^{22} to the ratchet electro-magnet E and printing electro-magnet D, thence by lines l^{23} to post p^5 , energizing these electro-magnets and drawing back the arm a^8 and pawl a^2 and the printing-hammer d' , to impress the paper against the type-wheels of the receiving-instrument. The main-line currents at the same time passing through the differential electro-magnets J and J' neutralize the same, releasing the tongue j and locking the type-wheel C by the arm j' engaging with the serrated wheel C^5 . Upon releasing a character-key the local circuit is broken at the indicator-segment b^{13} of the transmitter and the electro-magnet G is demagnetized, breaking the line-circuits at the springs g , g' , g^2 , and g^3 , stopping the double-line pulsations and interrupting the local circuit at the contact h' , the hammer d' recoils, and the lever-arm a^8 , drawn backward by the spring a^3 , moves the paper-carriage A^3 a space between two letters on both transmitting and receiving instruments.

If a character-key is depressed until a letter is impressed, and while the character-key is held down, the key b^8 in the local circuit is depressed, momentarily breaking the local circuit in the transmitter, the type-wheels C will remain at the same letter, while the breaking and closing of the line by the electro-magnet G will cause a repetition of the printing and feeding movements, thereby rapidly repeating the impression of any letter or character, and greatly increasing the speed of transmission. If, while both instruments are standing at unison, pulsations are sent simultaneously over both lines by making and breaking the branch local circuits of the transmitter at the key b^5 , the ratchet electro-magnet E and printing electro-magnet D of the transmitters and receivers will be actuated, and the paper-carriages will be moved simultaneously to space between paragraphs, the blank on the type-wheels at unison preventing the making of impressions.

The apparatus and electrical circuits for maintaining the paper-carriages in unison, and for placing any one or more of a series of receiving-instruments in circuit, and for cutting the operative parts out of circuit in the receiving-instruments for releasing the paper-carriage, and for feeding the paper between lines at any point in its excursion, will now be explained.

When the paper-carriage A^3 is released and recoils to the initial point of its excursion, an arm, a^{20} , attached to the frame of the paper-carriage, strikes the circuit-springs o^1 and o^2 of the automatic double-circuit switch O, closing them against the back contacts o^3 and o^4 , breaking the main-line circuits and closing the branch lines l^{12} and l^{13} , one line, l^{25} , passing

through one branch of the differential electro-magnet X and independent electro-magnet Y, and by line l^4 into the spring s^5 of the commutator S, and the other line, l^2 , in a reverse direction through the other coils of the differential electro-magnet X' and the independent electro-magnet Y', line l^5 , circuit-spring s^4 .

5 A circuit-breaker, W, Fig. 10, with a pointer, w , arm w' , and notched rim w^2 , is attached to each transmitter in a branch of one of the main-line circuits.

To the platform A', or elsewhere in each instrument used as a receiver or transmitter, are secured the differential electro-magnets X X' 15 and independent electro-magnets Y Y', one coil of each of the electro-magnets X and Y being in connection with the circuit-breaker W through the binding-post p , lines l^8 and l^9 , spring s^4 , line l^5 , independent electro-magnet 20 Y', differential electro-magnet X', line l^2 , circuit-springs o^2 o' , line l^6 , circuit-springs z^2 z^3 , and line l^9 to the binding-post p^3 . The other branch of the main line is connected from the binding-post p' through the electro-magnets 25 X and Y by line l^3 , one branch of the double-circuit breaker b^4 , normally-open line l^1 , circuit-spring s^5 , line l^4 , through the branch Y of the independent electro-magnet Y'; and in a reverse direction through the differential 30 electro-magnet X, line l^3 , circuit-springs o^4 and o^5 of the automatic circuit-breaker O, line l^8 , circuit-springs z^2 z^6 , line l^6 , and to the binding-post p^2 .

A branch line, l^6 , from the arm of key b^7 , 35 normally open, connects line l^8 with line l^9 , through this key when depressed. When the key b^7 is closed, it connects line l^9 with line l^1 . Lines l^7 and l^8 connect lines l^8 and l^9 with lines l^10 and l^11 when the double-circuit-closing 40 device b^4 is closed.

The individualizing circuit-breaker may have any number of divisions—that is to say, metallic contacts and insulations. The one shown in Fig. 10 of the drawings has twenty 45 four divisions, w^3 representing metallic contacts or makes, and w^4 insulations or breaks. This individualizing circuit-breaker W has a metallic hub, w^5 , insulated from its shaft, and insulated springs w^6 w^7 for effecting contacts 50 of makes and breaks corresponding with the metallic contacts w^8 and insulations w^9 on the periphery of the circuit-breaker W. The insulated spring w^7 bears upon the metallic hub w^5 in electrical connection with the contacts w^8 . 55 The arm w' and the pointer w are rigidly attached to the shaft of this circuit-breaker. A spring-click, w^9 , is attached to the arm w' , and the rim w^2 of the dial-plate is serrated with as many notches as there are metallic 60 contacts on the circuit-breaker W.

The dial w^2 should be numbered with figures corresponding with the number of insulations on the circuit-breaker W. When the index w indicates zero on the dial-plate, the individualizing circuit-breaker U on the platform A' of all the instruments in the series should

likewise stand at unison or zero, and the circuit-springs w^6 should bear on an insulation on the circuit-breaker W.

The individualizing circuit-closer U is carried on a shaft, u^4 , supported in bearings u^{13} and u^{14} , attached to the platform A' and carrying the double circuit-breaker U, the spiral or fusee u^5 , Fig. 7, the ratchet-wheel u^{10} , the metallic hubs u^{15} and u^{16} of the circuit closers insulated 70 from each other and from the shaft u^4 . This circuit-closer U has metallic contacts u^{17} u^{18} at corresponding points in their peripheries and in electrical connection with their respective hubs u^{15} and u^{16} . The insulated springs u^6 u^3 80 bear on the hubs, and the springs u^7 and u^8 bear on the periphery of the circuit-closer U.

The armature u^9 of the electro-magnet X is attached to a bent lever, u^8 , supported in trunnions u^{20} and u^{21} , which lever actuates a 85 pawl, u^{12} , when the electro-magnet X' is energized by the lines l^{18} l^{19} and branch lines l^{15} and l^{12} , leading from the circuit-breaker W of the transmitter, and revolves the ratchet-wheel u^{10} one notch at each make and break of circuit. There are, however, as many notches 90 on the ratchet-wheel u^{10} as there are contacts on the circuit-breaker W. A click attached to the platform A' prevents the retrograde movement of the ratchet-wheel u^{10} . A tongue, 95 u^6 , pivoted in trunnions u^{22} , is solicited laterally and vertically downward by suitable springs, u^{23} and u^{24} , causing the tongue u^6 to travel laterally by the rotation of the spiral or fusee u^5 until it arrests the shaft u^4 by contact 100 with the pin u^{11} . The armature u^{25} of the independent electro-magnets Y and Y' is attached to a bent lever, u^7 , supported in trunnions u^{26} . A retractile spring, u^{27} , is adjusted so as to resist the attraction of the single coil 105 of the electro-magnet Y'.

By revolving the arm w' of the circuit-breaker W twice, (the double switch O being open, as described,) and thereby sending pulsations through the coils of the electro-magnets X' and Y', the arm w' will come into contact with the pin u^{11} on the fusee or spiral u^5 in all the instruments and arrest the circuit-closers U in unison with the circuit-breaker W. Of course, it will be understood that the index w 115 of the dial-plate must point to zero when the circuit-closers are at unison.

When the key b^4 is depressed, and the circuits are simultaneously closed through lines l^{10} , l^{11} , l^{14} , l^{15} , l^{12} , and l^{13} and electro-magnets Y 120 and Y', the armature u^{25} will be attracted, while the electro-magnets X X' will neutralize each other, and the bent lever u^7 will release the unison arm or tongue u^6 from the stop u^{11} , and the springs u^{23} u^{24} of the arm u^6 will return 125 this tongue to its initial point, ready to commence its travel anew.

The metallic contacts w^{17} and w^{18} on the circuit-closer U are set at any number that may be desired—say at No. 1—so as to be brought 130 into contact with the springs u^7 and u^8 , when the ratchet-wheel u^{10} is moved one notch to close

the main-line circuit of the first receiver through springs u , u' , u^2 , and u^3 and lines l^7 , l^8 , l^9 , l^{10} around the automatic switch O .

Each instrument in the line has its metallic points u^7 and u^8 of the circuit-closer U set one division behind that of the metallic points on the circuit-closer of the preceding one, so that by turning the circuit breaker W each instrument in line is successively brought into and cut out of circuit until the instrument is reached upon which it may be desired to record impressions.

The method and manner of spacing between lines at any point in the excursion of the paper-carriage will now be described:

A square or feathered shaft, k^5 , is held within and supported by bearings on the frame A^3 of the carriage, moving therewith during its excursion. To this shaft k^5 is secured an arm, k , bifurcated at one end and engaging with a link, k^{10} , by means of suitable bearings. The arm k , held laterally by the arms k^9 , has a square or feathered hole permitting the shaft k^5 to move freely through it, yet preventing any rotation of it therein. A link, k^{10} , connects the arm k^{11} to the bent lever k^3 of the armature k^4 of the electro-magnet K . On the extremities of the shaft k^5 are fixed arms k^6 , carrying pawls k^7 , held in contact with the ratchets a^{15} by the spring k^8 .

Upon the depression of the key b^6 when the instruments in circuit stand at unison, and the main lines are broken at the circuit-breakers N , N' , but closed at the double switch, O , the branch lines l^{39} and l^{41} are closed at the spring s^5 , and thence through lines l^{22} , l^{21} , l^{20} , l^{16} , l^6 , l^9 to the binding-post p^3 into the main-line circuit. This pulsation energizes the electro-magnet K , and turns the ratchet a^{15} of the feed-roller a^{16} one notch, feeding the paper the space between two lines.

To release the paper-carriage at any point in its excursion, the key b^6 is depressed while the main-line circuits are open at the circuit-breakers N , N' at unison, closing the branch main lines l^{38} and l^{40} through the spring s^4 of the commutator S , thence by line l^{19} to the magnet L , and by lines l^{18} , l^{17} , l^7 to the binding-post p^2 , and thence to the other instruments in circuit or to ground. When the magnet L is energized by a pulsation on this line, its armature L , attached to its lever a^{27} , linked to an arm, a^{28} , pivoted to the shaft a^{25} , Fig. 6, or the armature L' may be secured to the arm a^{28} , as shown in Figs. 8 and 9, secured to the shaft of the automatic releasing T-shaped bar a^{19} , is attracted, oscillating this T-shaped bar laterally, and causing it to be locked by the spring-latch a^{24} , engaging with the pin a^{22} . This movement of the T-shaped bar a^{19} causes the pins a^{20} and a^{21} to release the dog a^4 and pawl a^2 from the rack A^6 , permitting the carriage at any point in its excursion to return to its initial point for presenting the left-hand margin of the paper to the type-wheel. The recoil of the carriage releases the T-shaped bar from its spring-latch a^{24} , as hereinabove fully explained.

The paper-carriage of the instruments connected in circuit are brought to unison by sending successive pulsations over both lines $7c$ by depressing the key b^6 while the type-wheels are at unison, which closes the branch local circuit through the relay G , thus closing both lines simultaneously and energizing the ratchet electro-magnet E , as hereinbefore described, on both the transmitting and receiving instruments. This causes the respective paper-carriages to travel until automatically released; or all the paper-carriages in the series may be released by depressing the key b^7 . When the paper-carriages recoil, the arm a^{30} , attached to the frame a^3 of the carriage, strikes the springs o' , o^3 of the automatic double switch O , breaking the main-line circuits through the compound relays H , H' , as previously described, and closing the branch circuits through the differential and independent electro-magnets XX' and YY' , respectively. The local circuit through the ratchet electro-magnet E cannot now be closed by the compound relays H , H' . The individualizing circuit-closers U are then revolved by turning the circuit-breaker W until the branch lines l^7 , l^8 , l^9 , and l^{10} are closed around the double switch O , which again restores the main-line circuits through the compound relays H , H' . This switch O is thereafter closed by the first movement of the paper-carriage A^3 , which restores the main-line circuits through the double switch O . The paper-carriages of the respective instruments will now, of course, start on their excursion in unison, and at each recoil movement of said carriages the interruption of the main-line circuits by the circuit-breakers Z will indicate to the operator the moment when each carriage is returning to its initial starting-point.

The main-line circuits for operating the magnets H , I , J , K , L , X , and Y by main-line batteries have been hereinbefore fully described; but I do not, however, confine myself to such method of operating them, as these magnets may be energized and operated by local-battery circuits controlled by relays in the main lines, in a manner well understood by persons skilled in electrical science.

Having thus described the nature and objects of my invention, what I claim as new, and desire to secure by Letters Patent, is—

1. The combination, in a printing-telegraph, of a transversely-traveling paper-carriage, wheels attached to said carriage and traveling over rails secured to a horizontal platform, a paper-roller held in bearings in the sides of said carriage, and feed-rollers journaled in the frame of said carriage below the plane of the type-wheel, said feed rollers operating to feed the paper upward through vertical and lateral straight guides, the said guides being so arranged that the paper is presented in a flat sheet in front of the type-wheel without obstruction to the impressions, substantially as described.

2. In printing-telegraphs, a double switch,

substantially as described, in each instrument, automatically operated by the recoil movement of a paper-carriage to interrupt the circuit through a compound relay employed to 5 close the local circuit through a ratchet electro-magnet operating to advance the paper-carriage in each receiver, and an individualizing-circuit breaker, substantially as described, operating from any transmitter in the circuit 10 to close the circuit in both transmitter and the receiver connected in the same main-line circuits around said automatic double switch, whereby the paper-carriages of a number of instruments connected in series are arrested at 15 unison, substantially as and for the purposes set forth.

3. The combination, in a printing-telegraph, of a transversely-traveling paper-carriage, wheels attached to said carriage and traveling 20 over rails secured to a horizontal platform, a paper-roller held in bearings in the sides of said carriage, vertical and lateral straight guides secured to said carriage, feed-rollers journaled in the frame of said carriage below 25 said guides, a spacing-rack attached to the lower part of said carriage, ratchets attached to said feed-rollers, clicks secured to the sides of said carriage for retaining said ratchets, and sliding arms movable vertically in supports 30 secured to said carriage, carrying pawls engaging in said ratchets, all arranged substantially as and for the purposes set forth.

4. The combination, in a printing-telegraph, of a transversely-traveling paper-carriage moving laterally in fixed supports and carrying 35 the paper-roller, feed-rollers, and spacing-rack, ratchets attached to said feed-rollers, clicks secured to the frame of said carriage for retaining said ratchets, sliding arms movable in 40 supports secured to said carriage and carrying pawls engaging in said ratchets, and a fixed incline plane engaging with said sliding arms, imparting thereto a vertically-reciprocating motion, substantially as and for the purposes 45 set forth.

5. The combination, in a printing telegraph, of a transversely-traveling paper carriage movable laterally in a horizontal plane on and between fixed supports, and carrying therewith 50 the paper-roller, feed-rollers, and spacing-rack, ratchets attached to said feed-rollers, clicks secured to the frame of said carriage for retaining said ratchets, sliding arms movable in supports 55 secured to said carriage and carrying pawls engaging in said ratchets, an incline plane attached to a fixed support engaging with said sliding arms, an automatic signaling-circuit interrupter, and a double-contact arm moving over the circuit-springs of said interrupter to 60 maintain a closed circuit during the forward movement of said paper-carriage, and over the insulations of said interrupter, during the retrograde movement of said carriage, substantially as and for the purposes set forth.

6. The combination, in a printing-telegraph, of a transversely-traveling paper-carriage, wheels attached to said carriage and traveling

over rails secured to a horizontal platform, a paper-roller held in bearings in the sides of said carriage, feed-rollers journaled in the 70 frame of said carriage below the plane of the type-wheel, vertical and lateral guides secured to said carriage, a rack actuated by a pawl attached to a lever, its armature actuated by a ratchet electro-magnet in the same electrical 75 circuit with a printing electro-magnet for moving said carriage step by step in one direction, and a spring or weight for returning said carriage in the opposite direction, substantially as described.

7. The combination, in a printing-telegraph, of a transversely-traveling paper-carriage, wheels secured to said carriage and traveling over rails secured to a horizontal platform, a paper roller held in bearings in the sides of said 80 carriage, feed-rollers journaled in the frame of said carriage, vertical and lateral guides secured to said carriage, a spacing-rack attached to said carriage, ratchets attached to feed-rollers supported in the frame of said carriage, 85 clicks secured to the sides of said carriage for retaining said ratchets, sliding arms movable in supports secured to said carriage and carrying pawls engaging in said ratchets, a printing-hammer and an electro-magnet attached to 90 a fixed support, and a ratchet electro-magnet in the same electrical circuit with said printing electro-magnet, substantially as and for the purposes set forth.

8. The combination, in a printing-telegraph, of paper-guides attached to a carriage traveling laterally within fixed supports for presenting the paper in a flat sheet and directing it vertically in front of the type-wheel without obstruction to the impressions, an electro-magnet, lever-pawl, dog, and rack to feed the paper step by step to space between letters, and an incline plane, pawl-arms, pawl, and feed-rollers to feed the paper vertically to space 105 between lines by the recoil movement of the paper-carriage during its excursion, substantially as hereinbefore set forth.

9. The combination, in a printing-telegraph, of a printing-hammer and an electro magnet attached to a fixed support in rear of the paper, a local circuit and printing and ratchet electro-magnets included in said circuit and energized thereby, and an armature-lever carrying a pawl and retracting-spring to move the paper-carriage when the circuit is interrupted, substantially as and for the purposes 115 set forth.

10. The combination, in a printing-telegraph, of a transversely-traveling paper-carriage, wheels secured to said carriage and traveling over rails secured to a horizontal platform, an arm attached to said carriage and moving therewith, an automatic double switch, and two telegraphic lines connected thereto, said arm at a predetermined point in its excursion actuating said double switch, substantially 125 as and for the purposes set forth.

11. The combination, in a printing-telegraph, of a laterally-traveling paper-carriage

carrying an arm which, at a predetermined point in its excursion, automatically actuates a double switch, breaking the line-circuits through the escapement and differential electro-magnets, and the compound relay controlling the local circuit, means, such as described, for again closing the main-line circuits through said electro-magnets, and means, such as described, for energizing the printing 5 electro-magnet and the ratchet electro-magnet moving said paper-carriage, substantially as and for the purposes set forth.

12. The combination, in a printing-telegraph, of a transversely-traveling paper-carriage moving over a fixed plane, said carriage carrying an arm which, at a predetermined point in its excursion, automatically breaks the main-line circuits through the escapement and differential electro-magnets and the compound 10 relay controlling the local circuit through the printing electro-magnet and the ratchet electro-magnet actuating the paper-carriage, and means, such as described, for closing said circuits, one of said line-circuits passing in one 15 direction through the coils of a differential electro-magnet and through one branch of an independent electro-magnet, and the other in a reverse direction through the coils of said differential electro-magnet and directly through 20 the other branch of the independent electro-magnet, substantially as and for the purposes set forth.

13. In a printing-telegraph, the combination, with a transversely-traveling paper-carriage carrying a paper-roller, fixed rollers, and spacing-rack, of ratchets attached to said feed-rollers, clicks for holding said ratchets in position, sliding arms movable in supports attached to said carriage, a fixed incline plane 25 engaging with said arms and imparting thereto a reciprocating motion, main-line-circuit contact springs and interrupters for signaling the movement of the paper and carriage, said carriage being moved step by step in one 30 direction by a pawl attached to a lever, an electro-magnet attached to a fixed support 35 actuating a lever through which moves freely a square or feathered shaft supported within the frame of the paper-carriage, and means, 40 such as described, for feeding the paper step by step between lines, and an armature actuated by an electro-magnet secured to a fixed support and operating a releasing device for 45 returning the carriage to its normal position 50 by the action of a spring or weight, substantially as and for the purposes set forth.

14. In a printing-telegraph, the combination, with an individualizing device consisting of a shaft, ratchet, contact-springs, and a unison-fusee, of a differential electro-magnet, with 55 its armature, lever, pawl, and retracting-spring for operating the ratchet of said individualizing device, and an electro-magnet with independent coils, with its armature, lever and 60 retracting-spring for releasing the unison-fusee of said individualizing device, substantially as and for the purposes set forth.

15. The combination, in a printing-telegraph, of a differential electro-magnet, with its armature-lever and pawls for actuating 70 ratchets, a circuit-breaker and unison-fusee on the ratchet-shaft, a pivoted unison-latch, and means, such as described, for releasing said unison-latch, substantially as and for the purposes set forth. 75

16. The combination, in a printing-telegraph, of a transversely-traveling paper-carriage, wheels attached to said carriage and traveling over rails secured to a horizontal platform, a spacing-rack attached to said carriage, a ratchet electro-magnet supported upon said platform, with its armature-lever, pawl, and spring for moving said carriage step by step in one direction, and an automatic releasing device, as described, secured to said platform and operated by said paper-carriage, for permitting the retrograde movement of the same, substantially as and for the purposes set forth. 80

17. The character-rods of a printing-telegraph transmitter in several horizontal series radiating from the center of and equidistant from one another around an indicator shaft and segment, and arranged in series vertically above each other, the number of rods in each horizontal series corresponding with the series of openings in the indicator-segment, and the entire 90 number of character-rods, including the unison-rod, corresponding with the divisions on the type-wheel, substantially as and for the 100 purposes set forth. 95

18. The combination, with the radial character-rods, of a printing-telegraph transmitter arranged in series vertically and horizontally, and susceptible of a reciprocating longitudinal movement, a metallic hub insulated from the indicator-shaft, metallic arms radiating from said hub at determinate angles and at heights, respectively, corresponding with the character-rods, and impinging against 105 said rods when longitudinally advanced, and an insulated metallic spring bearing on said hub, substantially as and for the purposes set forth. 110

19. The combination, in a printing-telegraph transmitter, of character-rods radiating from an indicator-shaft and arranged in series one above the other, the rods in each series equal to and corresponding with the series of openings in said indicator-segment and divisions 115 on the type-wheel, a segmental perforated indicator segment concentric with the indicator-shaft, and insulated arms on said shaft, arranged radially therefrom and in such positions as to impinge against said series of character-rods when longitudinally advanced, substantially as and for the purposes set forth. 120

20. The character-rods of a printing-telegraph transmitter, radiating from the center of and equidistant from one another around 125 an indicator-shaft and arranged in series above each other, each series equal in number to the openings corresponding therewith in the indicator-segment and the entire number of open-

ings equal to the divisions on the type-wheel, in combination with the bell-crank levers hinged to supporting steps of character key-
5 stems impinging against said bell-crank levers for advancing said rods horizontally, pins for limiting the forward movements of said rods, and springs for withdrawing said arms, substantially as described.

21. The character rods of a printing-tele-
10 graph transmitter, radiating from an indicator shaft, arranged in series corresponding with the number of openings in the indicator-segment, in combination with a unison-rod having an insulated contact of levers and pins op-
15 erating to withdraw said unison-rod by the ad-
vance of any character-rod, and vice versa, substantially as described.

22. The combination, in a printing - tele-
20 graph, of two telegraphic main lines, an auto-
matic double switch for breaking the main
lines and closing branches thereof through a
differential electro-magnet actuating the in-
dividualizing circuit-closer, an independent-
25 coil electro-magnet, and a circuit-breaker for
signaling included in said main lines, substan-
tially as and for the purposes set forth.

23. The combination, in a printing tele-
graph, of a differential electro-magnet with its
30 armature-lever and pawl, a click and ratchet
for revolving the circuit-breaker, the circuit-
breaker and contact being adjustable on its
shaft, and contact-springs for closing the cir-
cuit around the break in the main lines at the
35 automatic circuit-breaker, substantially as and
for the purposes set forth.

24. The combination, in a unison stop, of a
fusee on a revolving shaft, a unison latch and
pin susceptible of vertical and lateral motion,
40 and bearing on the spiral in said fusee, springs
for soliciting the latch vertically and laterally,
an armature-lever, retracting spring, and tripp-
ing-lever, and an electro-magnet with inde-
pendent coils for releasing the unison latch,
45 substantially as and for the purposes set forth.

25. The combination, in a printing - tele-
graph, of a local battery, ratchet and printing
electro-magnets, and a relay in the circuit of
50 said battery, said circuit being closed by con-
tact between the revolving arms and charac-
ter-rods, and a duplicating-key with its con-
tacts normally closed in said circuit, substan-
tially as and for the purposes set forth.

26. The combination, in a printing - tele-
55 graph, of a relay in the printing circuit, of a
transmitter energized by said circuit, with its
armature lever and contact-springs for simulta-
neously closing the main-line circuits, and a
compound relay in a receiver energized by
60 said circuits, substantially as and for the pur-
poses set forth.

27. The combination, in a printing - tele-
graph, of a battery and two telegraphic main
lines connecting the transmitting-instrument
with the receiving-instrument, with local bat-
65 teries and circuits for both instruments, com-
mutators for changing said line and local cir-
cuits, a loose sleeve on the type-wheel shaft

carrying scape-wheels, a unison-spiral, spac-
ing-wheel, and a clutch for connecting said
sleeve with the type-wheel shaft, thereby com-
70 bining the actuating parts of a receiver with
the same train of gearing, and motive power
employed for operating a transmitter, sub-
stantially as and for the purposes set forth.

28. The combination, in a printing - tele-
graph, of a battery, two telegraphic main lines
connecting the transmitting-instrument with
the receiving-instrument, local batteries and
circuits for both instruments, commutators,
80 such as described, for changing the line and
local circuits, means, such as described, for
combining the actuating parts of a receiver
with the same train of gearing, and motive
power employed for operating a transmitter,
85 and the local circuit of the transmitting-in-
strument closed by contact of the arms of the
indicator segment with any of the series of un-
insulated character-rods of said segment ad-
vanced endwise and broken by the withdrawal
90 thereof, substantially as and for the purposes
set forth.

29. The combination, in a printing - tele-
graph, of a battery, two main lines for connect-
ing a series of transmitters and receivers, local
95 batteries and circuits for the transmitters and
receivers, commutators, such as described, for
changing the line and local circuits, means,
such as described, for combining the actuating
parts of a receiver with the same train of gear-
ing, and motive power employed for operating
100 a transmitter, the local circuit of a transmitter
closed by contact of revolving arms with un-
insulated character-rods projected through an
indicator-segment and broken by the with-
drawal thereof, and the local circuit of a re-
105 ceiver closed by an electro-magnet responding
to double-line impulses, substantially as de-
scribed.

30. The combination, in a printing - tele-
graph, of a battery, two main lines, local bat-
110 teries and circuits for transmitters and re-
ceivers, commutators, such as described, for
changing the line and local circuits, means,
such as described, for combining the actuating
parts of a receiver with the same train of gear-
115 ing, and motive power employed for operating
a transmitter, the local circuit of a receiver
closed by an electro - magnet responding to
double-line impulses, the escapement, differ-
ential, and compound relay electro - magnets
120 of a receiver responding to alternate impulses
in the main lines, said compound relay at-
tracting both armatures, and the differential
electro-magnet inert by simultaneous pulsations
125 over both lines, substantially as and for
the purposes set forth.

31. The combination, in a printing - tele-
graph, of a battery and two main lines for
connecting the transmitter and receiver, local
batteries and circuits for the transmitter and
130 receiver, commutators, such as described, for
changing the line and local circuits, means,
such as described, for combining the actuating
parts of a receiver with the same train of gear-

- ing, and motive power employed for operating a transmitter, the local circuit of a receiver closed by an electro-magnet responding to double-line impulses, the escapement, differential, and compound relay electro-magnets of a receiver responding to alternate impulses over the main lines, said compound relay attracting both armatures by simultaneous pulsations, and the differential electro-magnet inert by simultaneous pulsations over both lines, and a relay in a local circuit of a transmitter with contacts to close the main lines simultaneously, substantially as and for the purposes set forth.
32. The combination, in a printing-telegraph, of a battery and two main lines for connecting the transmitter and receiver, local batteries and circuits for the transmitter and receiver, commutators, such as described, for changing the line and local circuits, means, such as described, for combining the actuating parts of a receiver with the same train of gearing, and motive power employed for operating a transmitter, the local circuit of a receiver closed by an electro-magnet responding to double-line impulses, the escapement, differential, and compound relay electro-magnets of a receiver responding to alternate impulses over the main lines, said compound relay attracting both armatures by simultaneous pulsations, and the differential electro-magnet inert by simultaneous pulsations over both lines, a relay in a local circuit of a transmitter with contacts to close the main lines simultaneously, a dial with a revolving individualizing circuit-breaker in a branch of the main lines of a transmitter, a key in a branch of the main lines of a transmitter to close both lines simultaneously, and keys in other branch circuits of a transmitter to close either main line, substantially as and for the purposes set forth.
33. The combination, in a printing-telegraph, of a battery, two main lines for connecting the transmitter and receiver, local batteries and circuits, commutators, such as described, for changing the line and local circuits, means, such as described, for combining the actuating parts of a receiver with the same train of gearing, and motive power employed for operating a transmitter, and a differential electro-magnet in both a transmitter and a receiver to revolve a circuit-closing device, substantially as and for the purposes set forth.
34. The combination, in a printing-telegraph, of a battery, two main lines, local batteries and circuits, commutators, such as described, for changing the line and local circuits, a differential electro-magnet in the transmitter and receiver to revolve a circuit-closer, and an electro-magnet with independent coils, and means, such as described, actuated thereby to release a unison-latch, substantially as and for the purposes set forth.
35. The combination, in a printing-telegraph, of a battery and two main lines, local batteries and circuits, a differential electro-magnet and an independent-coil electro-mag-

net in said circuits, a circuit-closer, and means, such as described, for revolving the shaft carrying the circuit-closer, a unison-fusee on said shaft, and means, substantially such as described, for locking the same at unison with the revolving circuit-locker at the zero-point of its dial, substantially as and for the purposes set forth.

36. The combination, in a printing-telegraph, of a battery and two main lines, local batteries and circuits, a differential electro-magnet and an independent-coil electro-magnet in said circuits, and means, substantially such as described, for actuating the same, an automatic double switch operated by the paper-carriage in its retrograde movement, breaking the main-line circuits through the compound relay, escapement, and differential electro-magnets, and closing the branch circuits around the same through the differential and independent-coil electro-magnets that actuate the rotary branch-circuit closer and release the unison-latch, a circuit-closing device, and means, such as described, for revolving the shaft carrying the circuit-closer and unison-fusee, and means, such as described, for locking the same at unison with an insulation on the circuit-breaker corresponding with zero on its dial, substantially as and for the purposes set forth.

37. The combination, in a printing-telegraph, of a battery and two telegraphic main lines, local batteries and circuits, a differential electro-magnet and an independent coil electro-magnet in said circuits, and means, substantially such as described, for actuating the same, a circuit-closing device, and means, such as described, for revolving the shaft carrying the circuit-closer, a unison-fusee, and means, such as described, for locking and releasing the same at unison with the revolving circuit-breaker in a transmitter, and an automatic switch operated by the paper-carriage in its retrograde movement, breaking the main-line circuits in the transmitter and through the compound relay, escapement, and differential electro-magnets of the receiver, and closing the branch circuits through the differential and independent-coil electro-magnets, the main-line circuits being again closed by branch lines connecting the springs brought into electrical contact by the revolving circuit-closer, substantially as set forth.

38. The combination, in a printing-telegraph, of a battery, two telegraphic main lines, a transversely-traveling paper-carriage moving in a horizontal plane, circuit-springs in said main lines attached to said carriage, and straight circuit-springs and insulations secured to said plane to maintain closed circuits in said main lines during the forward movement of the paper-carriage, and to interrupt the circuits in said main lines during the retrograde movement of said carriage, substantially as and for the purposes set forth.

39. The combination, in a printing-telegraph, of a battery, two telegraphic main lines,

circuit-breakers at the transmitter, an electro-magnet in a local circuit of the transmitter operating a double switch to close both lines when the printing circuit of the transmitter is closed, and an individualizing circuit-closer at the transmitter and receiver in the main lines, substantially as and for the purposes set forth.

40. The combination, in a printing - telegraph, of a battery and two main lines, circuit-breakers at the transmitter, an electro-magnet in a local circuit of the transmitter operating a double switch to close both main lines, an individualizing circuit-closer at the transmitter and receiver in the main lines, and an automatic switch, which by the movement of the paper-carriage breaks the main lines and closes a branch of said main lines, substantially as and for the purposes set forth.

41. The combination, in a printing - telegraph, of a battery and two main lines, circuit-breakers at the transmitter, an electro-magnet in a local circuit of the transmitter operating a double switch to close both main lines, an individualizing circuit-closer at the transmitter and receiver in the main lines, a unison device for said circuit-closer, and an automatic switch by which the movement of the transversely - traveling paper - carriage breaks the main lines and closes branch circuits of said main lines, substantially as and for the purposes set forth.

42. The combination, in a printing - telegraph, of a battery and two main lines, circuit-breakers at the transmitter, an electro-magnet in a local circuit, operating by means, such as described, for closing both main lines, an individualizing circuit-closer at the transmitter and receiver in the main lines, an automatic circuit-breaker which by the movement of the paper carriage breaks the main line and closes branch circuits thereof, and circuit-springs in contact with the circuit-closers included in a branch circuit to close the break in said main lines, substantially as and for the purposes set forth.

43. The combination, in a printing - telegraph, of a battery, two telegraphic main lines, circuit-breakers at the transmitter, an electro-magnet in a local circuit for actuating a double switch to close both main lines, an individualizing circuit-closer at the transmitter and receiver in the main line, a unison device and circuit-closer operated through single-line pulsation and released through simultaneous pulsations over both lines, a circuit-breaker and indicating-dial, and a double-line key in branch circuits of the main lines at the transmitter, substantially as and for the purposes set forth.

44. The combination, in a printing - telegraph, of a battery and two main lines, a branch of the main lines normally open in the transmitter connected to the main lines of the receiver at a point beyond where they are broken by the commutators, and passing through an electro-magnet responding only to prolonged impulses, said electro-magnet se-

cured to the supports carrying the paper-carriage, its armature-lever being connected to the shaft on which is pivoted the arm for automatically releasing the pawl and dog from the rack moving the paper-carriage, substantially as and for the purposes set forth.

45. The combination, in a printing - telegraph, of a battery and two telegraphic main lines, a branch of the main-line circuits normally open in the transmitter connected to the main lines of the receiver at a point beyond where they are broken by the commutator S, an electro-magnet in one of the main-line circuits, the armature-lever of said electro-magnet being connected to the shaft on which is pivoted the T-arm for automatically releasing the pawl and dog from the rack moving the paper-carriage, and a key, b⁶, in said branch circuit to send prolonged impulses to energize said electro-magnet, and operating to release the paper-carriages in both the transmitter and receiver at any point in their excursions, substantially as and for the purposes set forth.

46. The combination, in a printing - telegraph, of a battery and two telegraphic main lines, a branch of the main lines normally open in the transmitter connected to the main lines of the receiver at a point beyond where they are broken by the commutators, and passing through an electro magnet secured to supports carrying the paper-carriage, said electro-magnet being energized by sending prolonged impulses by a key in said circuit, its armature actuating a lever through which a square or feathered shaft pivoted on the paper-carriage freely moves, and arms attached to the ends of said shaft - carrying pawls engaging in the ratchet-wheels of the feed-rollers and operating when a key is depressed to feed the paper on both transmitter and receiver at any point in the excursion of the respective paper carriages, substantially as and for the purposes set forth.

47. The combination, in a printing - telegraph, of the electro-magnet K, secured to the platform carrying the paper-carriage, the armature-lever k³, linked to the arm k⁵, held laterally and sliding freely without revolving on its shaft, said shaft being secured between bearings supported on the paper-carriage, arms k⁶, and pawls k⁷ on said shaft for feeding the paper at any point in its excursion, substantially as and for the purposes set forth.

48. The combination, in a printing - telegraph, of the electro-magnet L, secured to the platform supporting the paper-carriage, the armature L', lever a²⁷, arm a²⁸, shaft a²⁵, and automatic releasing device a¹⁹, substantially as and for the purposes set forth.

49. The combination, in a printing - telegraph, of a unison device consisting of a fusee, u⁵, a latch, u⁶, springs u²³ u²⁴, magnets Y Y', with its armature u²⁵, bent lever u⁷, and retracting-spring u²⁷, substantially as and for the purposes set forth.

50. The combination, in a printing - telegraph, of a circuit-closing device consisting

of the differential magnet, X X', with its armature u^{19} , lever u^8 , and spring u^{28} , and the pawl u^{12} , ratchet-wheel u^{10} , dog u^{29} , circuit-closing contacts $u^{17} u^{18}$, and circuit-springs u , u' , u'' , u^3 , substantially as and for the purposes set forth.

51. The combination, in a printing - telegraph, with an automatic circuit-switch, such as described, operated by the recoil movement 10 of the paper-carriage to break the main-line circuits and to close a branch circuit, of a transversely-traveling paper-carriage, by the forward movement of which the automatic circuit-switch breaks the branch circuit and 15 closes the main line, substantially as and for the purposes set forth.

52. The combination, in a printing - telegraph, of a battery and two main lines, an indexed dial with its circuit-breaker in one line, 20 a circuit-closer and differential electro-magnet in said line, a branch circuit of said lines closed by an automatic switch, whereby the original main lines are broken, and means, substantially such as described, for revolving 25 said circuit-closer to restore the main lines around the switch without restoring the original main lines or breaking the branch circuit, substantially as and for the purposes set forth.

53. The combination, in a printing - telegraph, of a battery and two main lines, an indexed dial with its circuit-breaker in one line, 30 a differential electro-magnet and an independent-coil electro-magnet in branches of the main lines, and an automatic double switch, 35 whereby the course of the original main lines is changed from the escapement, compound relay, and differential electro-magnets of a receiver to said differential electro-magnet operating to revolve a circuit-closer to restore 40 the main lines around said double switch without restoring the original main lines through the same or breaking the branch circuits thereof, and said electro-magnet with independent coils in said branch circuits operating to release 45 the unison-latch of said circuit-closer, substantially as and for the purposes set forth.

54. The combination, in a printing - telegraph, of the insulated circuit-springs $z^2 z'$, the metallic bearings $z^4 z^9$ in electrical connection therewith, the insulations $z z'$, supported on the transversely-traveling paper-carriage A^3 , and the insulated bearing-springs $z^5 z^6$, secured to the platform A' , substantially as and for the purposes set forth.

55. The combination, in a printing - telegraph, of a battery and two main lines, an individualizing circuit-breaker, W, in a branch 50 of the main-line circuits normally open in the transmitter, the differential electro-magnets on the transmitter and receiver, one of the coils of each of said electro-magnets being brought into circuit with the circuit-breaker W through the operation of an automatic switch, and a circuit-closer revolved by said

electro-magnets, substantially as and for the 65 purposes set forth.

56. The combination, in a printing - telegraph, of a battery and two main lines, differential and independent-coil electro-magnets included in branch circuits of said main lines, 70 and an individualizing circuit-closer operated by said electro-magnets, substantially as and for the purposes set forth.

57. The combination, in a printing - telegraph, of a battery and two telegraphic main 75 lines, a double-line circuit-closing key, b^{40} , normally open in branches of said main lines, and an automatic double switch, O, for connecting the main lines to other branch circuits and the electro magnets X Y, included in the 80 latter branch circuits, substantially as and for the purposes set forth.

58. The combination, in a printing - telegraph, of an incline plane, a^{10} , having a projecting flange, a^{11} , fitting loosely into a notch, 85 a^{12} , the arms a^{13} , attached to a sliding dog, a^{14} , causing a vertical reciprocating movement of the paper-carriage without the intervention of springs, substantially as described.

59. The combination, with a printing telegraph, of an automatic device for releasing 90 the paper-carriage, consisting of a pivoted arm, a^{19} , pins $a^{20} a^{21} a^{22}$, spring-latch a^{24} , and arms $a^{26} a^{27}$, rigidly secured to the paper-carriage A^3 , substantially as described. 95

60. The combination, in a printing - telegraph, of a battery and two main lines, a key, b^1 , normally open in a transmitter in a branch of the main lines connected to one of the main lines beyond the commutator S, the electro-magnet L in the circuit of said main line, and the armature-lever of said electro-magnet connected to an automatic releasing device, as described, said electro-magnet, when energized by prolonged pulsations through the depression of said key, operating to release the paper-carriage at any point in its excursion, substantially as described. 100

61. The combination, in a printing - telegraph, of a battery and two main lines, a key, b^6 , normally open in a transmitter in a branch of the main lines, connected to one of the main lines beyond the commutator S, the electro-magnet K in the circuit of said main line, and with its armature-lever, link, shaft, and 105 pawls, said electro-magnet, when energized by prolonged pulsations through said key, operating to feed the paper step to step to space between lines at any point in its excursion, substantially as described. 110

In testimony whereof I have signed my name to the foregoing specification in the presence of two subscribing witnesses.

JACOB H. LINVILLE.
